UNITED STATES PATENT OFFICE.

OTTO SANN, OF JOHNSTOWN, PENNSYLVANIA.

GRINDING MACHINE.

Application filed March 28, 1925. Serial No. 19,005.

This invention relates to machines for grinding curved surfaces, and more particularly to a novel form of work supporting table for such machines, and has for its object the provision of a table of this class that will have a combined longitudinal and transverse movement relative to a fixed tool, so that a work-piece on the table will be moved through an arcuate path at the point of contact of the tool and said tool will grind an arcuate groove or surface in the work-piece.

Another object is to provide a table of this class that may be adjusted to have varying degrees of transverse movement, so as to provide for grinding grooves having different radii.

A further object is to provide a table of this class having the novel design, construction and combination of parts hereinafter described and illustrated in the accompanying drawings.

In the drawings:

Figure 1 is a plan view of a grinding machine table embodying my invention.

Figure 2 is a side elevation thereof.

Figure 3 is a plan view partly broken away to show the table mounting details.

Figures 4, 5, 6, and 7 are sectional elevations taken on the lines IV—IV, V—V, VI—VI, and VII—VII, respectively.

Figure 8 is an end elevation showing the table and tool or cutting head in their respective positions.

Referring more particularly to the drawings, the letter A designates the stationary base for the table, and the numeral 2 designates the slideable bed mounted on the base A and carrying the work supporting table 3.

The base A is composed of suitable side beam members 4 mounted on a suitable foundation or support 5. The beams 4 have their upper faces provided with suitable V-shaped grooves 6.

The bed 2 is provided with downwardly projecting rail portions 7, having beveled head portions 7^a which fit into the V-shaped grooves 6. The rails 7 serve as bearing supports and guides for the bed 2, which is adapted to be reciprocated longitudinally of the base A.

The work supporting table 3 is mounted on the bed 2 and is provided with a plurality of inverted T-shaped slots 10 in its top face for the reception of suitable mounting bolts used to secure or mount the work-piece on the table.

The table 3 is provided with an integral pivot bearing socket 11 adjacent its rear end, which is fitted over a pivot pin 12 mounted on the bed 2. The centers of the pivot bearing socket 11 and pin 12 intersect the longitudinal center line or axis of the table 3.

A suitable bearing plate 14 is mounted on the underside of the table 3 adjacent its forward end and is in sliding contact with a second bearing plate 15 on the bed 2 so as to provide a sliding bearing support for the forward portion of the table and permit the table to swing about the pivot pin 12 transversely of the bed 2.

A guide rail 16 having a guide flange 17 is slidably supported along one side of the table 3 on brackets 18 secured to the base A and to the foundation 5. A bracket arm 19 is secured to the rail 16 and extends under the base A and is mounted on a pivot pin 20 depending from a cross member 21 extending between the beam members 4 of the base. The center of the pivot pin 20 intersects the longitudinal center line or axis of the table 3.

The brackets 18 are provided with inverted T-shaped slots 22 in their head portions 23, which slots extend in a direction transversely of the bed 2, and in which are mounted suitable headed bolts 24 which extend through elongated openings or slots 25 in the guide rail 16, which slots extend in a line parallel with the longitudinal axis of the rail. The bolts 24 are provided with suitable nuts 24^a which are adapted to be tightened to lock the rail in adjusted positions.

A guide arm 27 has one end pivotally mounted on a pivot pin 28 secured in the table 3 with its center intersecting the longitudinal center line or axis of the table, at a point spaced from the free forward end of said table a distance equal to the distance that the pivot pin 12 is spaced from the rear or pivot supported end of the table. The other end of the arm 27 is provided with a guide head 29 which is fitted over the guide flange 17 of the rail 16.

In operation the guide rail 16 is adapted to be moved about the pivot pin 20 and locked in an angular position relative to the longitudinal axis of the table 3. The table 3 is then reciprocated by reciprocating the bed 2, and as the bed and table reciprocate, the table 3 will be swung about the pivot pin 12 so as to move transversely of the bed 2 due to the pull of the guide arm 27 as it

travels along the angularly positioned guide rail 16.

The combined longitudinal movement and transverse swinging movement of the table 3 5 will thus cause the work-piece secured to the table to be moved through an arcuate path at the point of contact of the work-piece with a fixed tool, to be described, so that said tool will cut an arcuate groove or path 10 in the work-piece.

Any suitable tool supporting structure and tool may be provided for cutting the arcuate grooves or surfaces on the work-piece. In the drawings, Figure 8, I have 15 shown a tool bridge B comprising upright side members 30 and a transverse bridge member 31. A suitable tool head 32 is slidably mounted on the side members 30 and adapted to be moved laterally thereof. The 20 tool head 32 is provided with a motor 33 which is operatively connected by a belt 33a to a tool operating shaft 34, which shaft in the present construction carries a grinding wheel 35 adapted to grind the groove or 25 surface in a work-piece.

While this machine is primarily adapted for grinding or cutting arcuate grooves in track structures such as switches, crossings and the like, it will be understood that I do 30 not wish to be limited to such use, and that various tools may be substituted for the grinding wheel 35 to cut the arcuate grooves or surfaces in any form of work-piece.

I claim:

35 In a machine for cutting curved or arcuate grooves or paths in a work-piece, a sta-

tionary base member, a bed slidably mounted on said base and adapted to be reciprocated longitudinally thereof, a work supporting table mounted on said bed, said table being pivotally connected to said bed adjacent one end and slidably supported on said bed adjacent the other end whereby said table may be swung about said pivot transversely of said bed, a tool mounted 40 above said table, a guide rail extending along one side of and longitudinally of said bed and arranged at an angle to the longitudinal axis of said bed, a bracket arm for supporting said guide rail, said bracket arm having one end fixedly secured to said guide rail intermediate its ends and having its 45 other end pivotally mounted on a fixed pivot pin whose center line intersects the longitudinal center line or axis of said bed, means for moving said rail about said pivotal mounting of said bracket arm, means for locking said rail in adjusted positions, and a guide arm mounted to travel along said rail, said arm being pivotally connected to 50 said table at a point spaced from the slidably supported end of the table a distance equal to the distance the pivotal mounting of the table is from the opposite end of the table, whereby said table will be swung 55 transversely of said bed as said bed and table are reciprocated longitudinally so as to cause the tool to cut an arcuate path in the work-piece carried by said table.

In testimony whereof, I have hereunto set 60 my hand.

OTTO SANN.
